(57) **CLAIM**

The ornamental design for a spherical light, as shown and described.

DESCRIPTION

FIG. 1 is a front elevational view of a spherical light showing my new design;

FIG. 2 is a rear elevational view thereof;

FIG. 3 is a left side view thereof;

FIG. 4 is a right side view thereof;

FIG. 5 is a top plan view in enlarge scale thereof;

FIG. 6 is a bottom plan view in enlarge scale thereof;

FIG. 7 is a perspective view thereof; and,

FIG. 8 is a second perspective view thereof.

The broken lines shown in FIG. 6 are included for the purpose of illustrating portions of the spherical light and form no part of the claimed design.

1 Claim, 8 Drawing Sheets

FIG. 1

FIG. 2
